FIGURE TOY

David H. Wilner, Los Angeles, Calif.

Application January 3, 1949, Serial No. 23

Term of patent 14 years

(Cl. D34—15)

To all whom it may concern:

Be it known that I, David H. Wilner, a citizen of the United States, residing at Los Angeles, in the county of Los Angeles and State of California, have invented a new, original, and ornamental Design for a Figure Toy, of which the following is a specification, reference being had to the accompanying drawing, forming part thereof.

Fig. 2 is a view in side elevation thereof.

Fig. 3 is a front elevation of the figure toy shown in Figs. 1 and 2.

Fig. 4 is a rear elevational view of said figure toy.

I claim:

The ornamental design for a figure toy, as shown.

DAVID H. WILNER.
